UNITED STATES PATENT OFFICE.

EDWARD M. HALL, OF CARTHAGE, NEW YORK.

BUR FOR TREATING GRINDSTONES.

1,219,299.

Specification of Letters Patent. Patented Mar. 13, 1917.

Application filed December 28, 1915. Serial No. 63,977.

To all whom it may concern:

Be it known that I, EDWARD M. HALL, a citizen of the United States, residing at Carthage, in the county of Jefferson and State of New York, have invented new and useful Improvements in Burs for Treating Grindstones, of which the following is a specification.

It is my object to provide a bur for treating the surface of wood-pulp grindstones, so constructed that, when used by unskilled laborers, the surface of the stone will, with certainty, be properly treated, and without danger of injury to the grindstone. It has been the custom to treat grindstones with a rotating bur pressed firmly against, and moved across, the surface of the stone. As the grindstone rotates, a rotary motion is imparted to the bur, the teeth of which bite into the surface of the stone and, by the movement of the bur across the stone, produce therein depressions, corresponding in shape and dimensions to the teeth of the bur. A bur commonly used is provided with transverse, diagonally-disposed V-shaped teeth, separated by similar V-shaped channels which produces in the face of the stone correspondingly-shaped teeth and depressions.

A grindstone having a surface of that character is poorly adapted for the production of a uniform quality of wood fiber, for the reason that the sharp pointed teeth at first produce a considerable percentage of very short length fiber and sawdust, and, after the stone has been in use for some time, the teeth are broken down unevenly, and when in this condition the stone produces a small percentage of uniform fibers, the result is that a stone provided with sharp, V-shaped teeth cannot produce wood pulp containing a sufficient percentage of fiber of that degree of uniformity best suited for the manufacture of news print paper; and the careless use of such a bur may result in serious injury to the stone. The most desired surface for a grindstone is one in which depressions, diagonally-disposed from side to side across the stone, are separated by flat-top ridges,

constituting the abrasive surfaces which serve to tear off the fiber from the wood. It is difficult, however, if not impossible, to use a bur of the character described to produce such desired surface.

My invention consists in a bur having transverse V-shaped teeth, separated by channels, the bottoms of which are substantially flat and serve not only to definitely limit the depth to which the teeth will be driven into the stone to produce the depressions, but also to secure alternate flat-topped ridges.

In the drawings forming a part hereof Figure 1 is a front view and partly in section, and Fig. 2 is a part end view of Fig. 1, showing a bur constructed according to my invention, with diagonally-disposed teeth, and Figs. 3 and 4 are similar views of a bur having teeth substantially parallel with its axis.

The bur 1, which may be either solid or a hollow cylinder, has formed on its peripheral surface, at any desired distance apart, V-shaped teeth 2, separated by channels 3, the bottoms of which constitute the peripheral surface of the bur, and hence are substantially flat.

Such a bur may be used by an unskilled laborer without any danger of injury to the stone, and with the certainty of producing in the stone the desired surface, and always producing a definite uniform pattern, the bottoms of the channels 3 on the bur serving to limit the depth of the depressions cut by the teeth 2, and at the same time to obtain the flat-top ridges in the stone between the depressions.

I claim as my invention:

A bur for use in treating the surface of grindstones, having teeth upon its peripheral surface, said teeth being separated by channels, the bottoms of which are substantially flat and which serve to limit the depth to which said teeth may be driven into the surface of the grindstone and to secure alternate flat-top ridges.

EDWARD M. HALL.
